(57) **CLAIM**

The ornamental design for a skate blades imprisoned into faded ice blocks, as shown and described.

DESCRIPTION

FIG. 1 is a perspective view of a skate blades imprisoned into faded ice blocks, according to a first embodiment;

FIG. 2 is a rear view of a skate blades imprisoned into faded ice blocks, according to a first embodiment;

FIG. 3 is a front view of a skate blades imprisoned into faded ice blocks, according to a first embodiment;

FIG. 4 is a right side view of a skate blades imprisoned into faded ice blocks, according to a first embodiment;

FIG. 5 is a left side view of a skate blades imprisoned into faded ice blocks, according to a first embodiment;

FIG. 6 is a top view of a skate blades imprisoned into faded ice blocks, according to a first embodiment;

FIG. 7 is a bottom view of a skate blades imprisoned into faded ice blocks, according to a first embodiment;

FIG. 8 is a perspective view of a skate blades imprisoned into faded ice blocks, according to a second embodiment;

FIG. 9 is a rear view of a skate blades imprisoned into faded ice blocks, according to a second embodiment;

FIG. 10 is a front view of a skate blades imprisoned into faded ice blocks, according to a second embodiment;

FIG. 11 is a right side view of a skate blades imprisoned into faded ice blocks, according to a second embodiment;

FIG. 12 is a left side view of a skate blades imprisoned into faded ice blocks, according to a second embodiment;

FIG. 13 is a top view of a skate blades imprisoned into faded ice blocks, according to a second embodiment; and,

FIG. 14 is a bottom view of a skate blades imprisoned into faded ice blocks, according to a second embodiment.

The broken line showing of structure is included for the purpose of illustrating portions of the skate blades imprisoned into faded ice blocks and forms no part of the claimed design.

1 Claim, 7 Drawing Sheets
